UNITED STATES PATENT OFFICE.

ABEL FISHER, OF WELLSVILLE, OHIO.

APPARATUS FOR SPRAYING PAINT.

SPECIFICATION forming part of Letters Patent No. 653,292, dated July 10, 1900.

Application filed April 9, 1898. Serial No. 676,974. (No model.)

To all whom it may concern:

Be it known that I, ABEL FISHER, a citizen of the United States of America, residing in Wellsville, in the county of Columbiana, in the State of Ohio, have invented certain new and useful Improvements in Spraying Apparatus, of which the following is a true and exact description, reference being had to the accompanying drawings, which form a part thereof.

My invention relates to the construction of apparatus for applying paint in the form of a spray, such in general character as that described in my former patents, No. 584,864, of June 22, 1897, and No. 593,013, of November 2, 1897, my invention being, in fact, an improvement upon my apparatus as described and shown in the said patents, and my object being, in the first place, to provide an improved construction of the spraying-head; in the second place, a better and simpler device for operating the valves, the admission of air and paint to the spraying-head, and, finally, the improvement of various details of construction.

The nature of my improvements will be best understood as described in connection with the drawings in which they are illustrated, and in which—

Figure 1 is a sectional side elevation of my improved paint-spraying apparatus, taken on the section-line 1 1 of Fig. 3. Fig. 2 is a rear end elevation of the device; Fig. 3, a plan view thereof; Fig. 4, a side view of the spraying-head; Fig. 5, a section through the head taken as on the line 2 2 of Fig. 4; Fig. 6, a section through the head taken as on the line 3 3 of Fig. 4. Fig. 7 is a perspective view showing the inside of one of the caps used in forming the spraying-head, and Fig. 8 is a perspective view of the spraying-head with one cap removed.

A indicates the fixed handle of the device, flanged at top, as indicated at A', and secured in any convenient way to the lower part of the paint-chamber B, which, as shown, is formed in a casting open at the top, and in which casting are also preferably formed, as shown, various other passages and chambers, which may be described as follows:

B' is a tubular extension from the paint-chamber B, through which the paint is intro-

duced thereto, preferably by means of a flexible pipe C, clamped at its end, as indicated at C', C² indicating a pipe screwing into the tubular section B' on the inside of the paint-box and having at its inner end an oblique valve-seat C³, as indicated. B² is another tubular extension of the casting, opening at one end into the paint-chamber, and at the other end broadening out, first, into a packing-chamber b² and then into an air-chamber B³, from which extends a tubular section B⁴. The air-chamber B³ connects also through a valve-seated passage b³ with a second air-chamber B⁵, from which extends the tubular section B⁷, to which the flexible air-supply pipe K is secured, as by a clamp K', and also the tubular opening B⁶, formed opposite to the valve-seat b³, to provide means for inserting and removing the valve, the said valve being indicated at L and provided with a valve-stem L', which extends through the tubular opening B⁶ and around which are placed the washer L², abutting against a shoulder in the passage, and the screw-plug L³, between which and the washer L² packing is clamped to make a tight joint around the valve-stem.

L⁴ indicates a pin or pins on the outer end of the valve-stem L'.

D is a cap fitting on the open end of the paint-box B, and between which and the top edge of the said paint-box is clamped the flexible diaphragm E, having a perforation at its center. The cap or top piece D is preferably formed, as shown, with a tubular central projection D', closed by a screw-plug D², conveniently operated by a thumb-wheel D³, and perforated, as indicated at d², for the passage of the valve-stem F'. The said valve-stem is secured to the diaphragm E, through which it passes, by a flange F², resting against the under side of the diaphragm, and nuts, as indicated at F², screwing on the valve-stem and by which the diaphragm is clamped against the flange F³. Below the diaphragm the valve-stem is continued at an angle, as indicated at f, and holds a valve F, which fits against the valve-seat C³, and to keep it in alignment some guiding device should be provided—such, for instance, as a slotted end, (indicated at f'), in the slotted portion of which lies a projection, as b.

G indicates a spring resting against the

adjustable plug D² at its upper end and against the nuts F² at its lower end and by means of which the pressure in the chamber B is regulated, the valve F being, as in my 5 former constructions, a regulating-valve by which the supply of paint to the chamber B is cutoff when the pressure in said chamber exceeds a determined amount.

H H³ indicate the paint-supply pipe leading 10 from the chamber B to the spraying-head. The portion H of this tube is formed to fit in the tubular extension B² and is provided at its end projecting into the chamber with a valve-seat, as indicated at H', and at the 15 other end of the tube-section B² with a flange H², fitting in the packing-chamber b².

I is a valve adapted to close the connection 20 between the chamber B and the pipe H when it rests on the valve-seat H'. As shown, it 25 is made of a yielding material, such as leather, secured in a cup-shaped cavity in the end of a valve-rod I', which extends through a packing-chamber at the rear of chamber B, closed by a screw-plug I², and has its outer end 30 threaded, as indicated at I⁴, so that a nut I⁵ will screw upon it and serve to connect it with an arm J, from which arm a right-angled 35 extension J' extends through a guiding-bearing A² in the grip A. A spring G' serves to hold the valve I normally seated on the valve-seat H'.

M³ is a movable grip-lever secured to the 40 stationary grip A through a spring G² and having formed with or secured upon its upper end two plates, one of which at M is slotted, as indicated at M', to engage the pins L⁴ of the valve-stem L' and having a cross-bar M², arranged in position to impinge against the 45 end of the rod J' when the grip-lever is actuated.

m' indicates a recess or tooth formed on the 50 under side of the paint-box or its extension B² and adapted to engage a toe m at the extreme upper end of the plate M when the grip-lever 55 is drawn back toward the fixed grip, the engagement being of such a character as to partly, but not wholly, overcome the tendency of the spring G² to return the parts to the position shown in Fig. 1.

N is the air-tube leading to the spraying-head, and it is formed with a flange N', fitting 60 in the tubular extension B⁴ and between which and the flange N' packing material is inserted.

N³ is an annular screw-plug screwing in the 65 end of the tubular extension B⁴ and provided with a thumb-wheel n³, and M⁴ is a jam-nut screwing on that portion of the plug N³ which lies outside of the tubular extension B⁴, the 70 arrangement being such as to form a tight joint around the air-tube N, while permitting the said tube and the head attached to it to turn freely, and in the particular construction shown, as the tubes N and H³ are both 75 secured to the center O of the spraying-head, the plug N³ also serves to set the flange H² of the paint-tube up against the packing mate-

rial, which makes a tight joint between the tube B² and the air-chamber B³.

The head or spraying-nozzle of the apparatus is made up of three parts—one the center O and the caps P P. The said center O is preferably made, as shown, with two conical ends (indicated at O¹⁰ O¹⁰) separated by a narrow cylindrical portion O⁴, and as a convenient way of attaching the caps I prefer to provide a threaded stud O⁹, extending out from the end of each conical section. The air-tube N enters an opening O' in the center O and is permanently secured thereto. Channels 80 O² O² are formed in the center and connected in turn with the faces of the conical ends of the center by ports O⁸. The paint-tube H³ enters the center through a perforation O⁶, to which it is secured and which perforation 85 connects by a port O⁷ with a flared port O⁸, opening through the center O⁴, as indicated, and preferably flanked on each end by projections O⁵ O⁵.

P P are caps fitting over the conical ends 90 of the center, with their edges forming tight joints, as indicated at P⁴, with the outer portion of the caps, the caps being preferably secured in nuts P', through which the studs O⁹ extend, clamping-nuts Q screwing on the outside of the studs. The caps are of course recessed, as indicated at P², (see Fig. 7,) to extend around the pipe N, and they are provided, in addition to their joint-forming edges P⁴, with joint-forming webs P³ and flanges P⁵ 100 P⁵, which fit against the conical face O¹⁰, over which the caps rest, and form the chambers R and R', the purpose of the flanges P⁵, which divide these chambers from each other, being to insure a movement of the air first from 105 the center in passing through and from the chambers R', which open through ports P⁶ on each side of the port O⁸, as indicated after Figs. 1 and 4, the two air-jets converging on 110 each other over the face of the port O⁸.

In operation the paint-chamber B is kept supplied with paint at a determined pressure, as described in my former patents, and flexible pipe L is connected with some source of air under pressure. When the operator desires to throw a jet of paint in the form of spray from the head, he grasps the fixed and movable grip-levers A and M³ and draws the movable lever inward, thus by means of the engagement of the slots M' and pins L⁴ drawing the valve-stem L' outward and opening the valve L, permitting the compressed air to enter the air-chamber B³, from which it passes through the tube N and the passages O² and O³ into the chambers R and thence through the 125 chambers R' out of the converging air-nozzles P⁶ P⁶. Continuing the inward movement of the grip-lever, the operator brings the plate M² into contact with the end of the rod J', forcing it backward, and through its arm J 130 and the valve-stem I', opening the valve I, permitting the paint to flow from the chamber B through the paint-tube H H³ and the port O⁷ into the flared port O⁸, the paint emerg-

ing from the said port into the converging air-jets, which break it up and carry it to the surface to be painted in the form of a spray, the outwardly-projecting flanges or lugs O^5 serving to prevent any dripping or weeping of the paint at the edges of the flared port. When the backward movement of the grip-lever M^3 reaches the normal operative position, the toes m of the plates M pass into and are engaged by the notch or recess m' , which has the effect of greatly relieving the power necessary to hold the grip-lever in operative position, while at the same time the engagement is not sufficiently rigid to entirely overcome the tendency of the spring G^2 to return the movable grip-lever to its normal position.

Having now described my invention, what I claim as new, and desire to secure by Letters Patent, is—

1. A spraying-head having in combination the center O formed with conical ends $O^{10} O^{10}$, a fluid-port as $O^7 O^8$ opening from its center and air-ports as $O^2 O^3$ opening through its conical sides and the caps $P P$ adapted to fit over the conical ends of the center O and form air-chambers as R' having ports as P^6 opening on the edge of the air-port O^3 .

2. A spraying-head having in combination the center O formed with conical ends $O^{10} O^{10}$, a fluid-port, as $O^7 O^8$, opening from its center, outwardly-extending end walls $O^5 O^5$ at each end of the fluid-port, and air-ports as $O^2 O^3$ opening through its conical sides and the caps $P P$ adapted to fit over the conical ends of the center O and form air-chambers as R' having ports as P^6 opening on the edge of the air-port O^3 .

3. A spraying-head having in combination the center O formed with conical ends $O^{10} O^{10}$, a fluid-port, as $O^7 O^8$, opening from its center, and air-ports as $O^2 O^3$ opening through its conical sides, and the caps $P P$ adapted to fit over the conical ends of the center O and formed with partitions $P^5 P^5$ whereby air-chambers $R R'$ are formed on each side of the center the outer chambers R' having ports as P^6 opening on the edge of the fluid-port O^3 .

4. A spraying-head having in combination the center O formed with conical ends $O^{10} O^{10}$, a fluid-port, as $O^7 O^8$, opening from its center, outwardly-extending end walls $O^5 O^5$ at each

end of the fluid-port, and air-ports as $O^2 O^3$ opening through its conical sides and the caps $P P$ adapted to fit over the conical ends of the center O and formed with partitions $P^5 P^5$ whereby air-chambers $R R'$ are formed on each side of the center the outer chambers R' having ports as P^6 opening on the edge of the fluid-port O^3 . 55

5. A spraying-head having in combination the center O formed with conical ends $O^{10} O^{10}$, a fluid-port as $O^7 O^8$ opening from its center, air-ports as $O^2 O^3$ opening through its conical side and threaded studs $O^9 O^9$ extending from the ends of the conical ends and the caps $P P$ 65 adapted to fit over the studs and the conical ends of the center O and form air-chambers as R' having ports as P^6 opening on the edge of the air-port O^3 .

6. In a painting-nozzle the paint-chamber B and air-chamber B^3 connected by a tube B^2 and said air-chamber connected with a threaded tubular section B^4 in combination with a spraying-head, an air-tube N secured to the head and having a flange N' fitting in the 75 tubular section B^4 , a paint-tube H H^3 also secured to the head, extending through the tube N , chamber B^3 and tube B^2 into the paint-chamber, a packing-flange as H^2 secured on the paint-tube and adapted to make a tight 80 joint between the chamber B^3 and tube B^2 and a threaded packing-annulus as $N^3 n^3$ fitting on tube N and screwing in the tube B^4 so as to hold packing between its end and the flange N' of tube N . 85

7. In a painting-nozzle, substantially as described, the combination of valves L and I for regulating the admission of air and paint into the tubes leading to the head with a spring-supported grip-lever M^3 normally resting in position to permit the valves to remain closed, valve-actuating devices arranged to be acted on by the lever M^3 when it is moved and whereby the valves L and I are successively opened, and a detent as m' arranged to 90 engage and partially hold the grip-lever when moved to its normal valve-opening position. 95

ABEL FISHER.
